UNITED STATES PATENT OFFICE.

ISAAC H. MILLIKEN, OF ASPINWALL, PENNSYLVANIA, ASSIGNOR TO THE McCONWAY & TORLEY COMPANY, OF PITTSBURGH, PENNSYLVANIA, A CORPORATION OF PENNSYLVANIA.

CAR-COUPLING.

1,227,170.

Specification of Letters Patent. Patented May 22, 1917.

Application filed November 4, 1916. Serial No. 129,437.

To all whom it may concern:

Be it known that I, ISAAC H. MILLIKEN, a citizen of the United States, residing at Aspinwall, in the county of Allegheny and State of Pennsylvania, have invented certain new and useful Improvements in Car-Couplings; and I do hereby declare the following to be a full, clear, and exact description of the invention, such as will enable others skilled in the art to which it appertains to make and use the same.

My invention relates to the construction of car couplers of the Master Car Builders' type and particularly to the locking mechanism thereof. The primary object of the invention is to provide means whereby the locking mechanism of a coupler may be interchangeably assembled with different well-known forms of lock actuating devices, thus rendering it unnecessary to provide a different form of lock for assembly with each type of lock actuating mechanism, and thereby reducing the number of repair parts required to be carried in stock by the railroad company. A further object of the invention is to provide a simple, strong and efficient form of knuckle lock for use in a car coupler having lock-set and knuckle opening devices.

In the drawings illustrating the preferred embodiment of my invention, the scope whereof is pointed out in the claims,

Figure 1 is a side elevation of a coupler mechanism embodying my invention, the lock actuating device being of the type involving a pivoted lifter member arranged and operating in a vertical plane extending longitudinally of the coupler.

Fig. 2 is a front elevation of a coupler mechanism embodying my invention, the lock actuating device being of the type involving a pivoted lever operating in a vertical plane extending transversely of the coupler head, and the interior mechanism of the coupler being shown in dotted lines.

Fig. 3 is a detail side elevation of the coupler lock looking from the knuckle side of the coupler head.

Fig. 4 is a detail front view of the coupler lock, showing the lock-set member assembled therewith.

Fig. 5 is a sectional view taken on the line 5—5, Fig. 4, looking toward the lower end of the lock.

Fig. 6 is a section on the line 6—6, Fig. 4, looking downwardly; and.

Fig. 7 is a plan view of the upper end of the lock, showing the lock-set member assembled therewith.

In the drawings, 1 is the coupler head and 2 is the knuckle pivotally mounted thereon. The lock 3 co-operates with the tail 4 of the knuckle in the usual manner to retain the knuckle 2 in coupled position, as indicated in dotted lines in Fig. 2.

In the construction shown in Fig. 1 the lock 3 is adapted to be lifted by means of a vertically swinging actuating arm or lever 5 that extends longitudinally of the coupler, said lever being provided at its rear end with oppositely projecting trunnions 6 by which it is pivotally mounted in a bracket 7 secured to the coupler. In the construction shown in Fig. 2 the mechanism for actuating the lock 3 involves a bell-crank lever 8 that operates in a vertical plane transversely of the coupler head, such head being provided with pivot lugs 9 adapted to receive a pivot pin 10 by which the lock actuating lever 8 is connected to the coupler head.

Both of these types of lock actuating mechanism are in use and well known to those skilled in the art.

The lock 3, which projects downwardly below the coupler head, is provided near its lower end with a plurality of openings 11 and 12, respectively, which extend at right angles to each other. The opening 11, which is adapted to receive the forward end of the longitudinally extending actuating member 5, preferably extends below the opening 12 that receives the bell-crank lifting lever 8, and, as shown, the said openings 11 and 12 preferably overlap and communicate with each other as such a construction reduces the extent to which the lock 3 is required to project below the coupler head.

The lock engaging end of the actuating member 5 is preferably formed with a locking shoulder 13, and the lock 3 is formed at the base of the opening 11 therein with a corresponding locking face 14, the locking faces 13 and 14 being adapted to bind upon each other when the lock 3 accidentally attempts to execute an unlocking movement, thereby preventing accidental unlocking of the coupler. When the pivoted actuating member 5 is swung upwardly by the rod 15,

the locking faces 13 and 14 are first released from coöperative relation and the upper surface 16 of the outer end of the actuating member 5 thereafter engages the face 17 of the lock at the upper end of the slot 11 therein and causes said lock to perform an extended unlocking movement. The lock engaging end of the bell-crank actuating lever 8 is similarly formed with a locking face or shoulder 18 which is adapted to contact and bind upon a corresponding shoulder 19 of the lock to prevent accidental unlocking of the latter, as will be seen upon reference to Fig. 2 of the drawings.

15 Near its upper end and on the side toward the knuckle 2 the lock 3 is provided with a lug or projection 20 that is adapted to engage and operate one arm of a bell-crank knuckle opener 21 that is pivotally mounted 20 within the coupler head in a well known manner. Adjacent to the projection 20 the lock is formed with a slot 22 which receives a lock-set member 23 that is pivotally mounted on said lock by means of a pivot pin 24 25 which passes through appropriate openings 25 and 26 in the lock. When the lock 3 is in locked position the lock-set member 23 rests in a horizontal position on the upper surface of the tail 4 of the knuckle, but when the 30 lock is raised to unlocked position preliminary to separating the cars the lock-set member 23 gravitates to a vertical position and its lower end rests upon the upper surface of the knuckle tail, thus maintaining the lock 35 in an elevated or unlocked position.

I claim:

1. A coupler lock having a plurality of intersecting openings extending at an angle

to each other, each of said openings being adapted to receive means for moving said 40 lock to unlocked position.

2. A coupler lock having a portion adapted to project downwardly outside the head of a coupler, said projecting portion being provided with two openings, one of said 45 openings extending longitudinally of the coupler and the other of said openings extending transversely of said coupler, and each of said openings being adapted to receive means for moving said lock to unlocked 50 position.

3. A coupler lock having a plurality of overlapping openings extending at an angle to each other, each of said openings being adapted to receive means for moving said 55 lock to unlocked position.

4. A coupler lock having on one side a projection adapted to engage a knuckle opening lever, and being provided adjacent said projection with a slot opening through 60 the said lock to receive a lock-set member and permit it to extend beyond the same face of said lock from which said projection extends.

5. In a car coupler, the combination with 65 a coupler head, of a knuckle pivoted thereon, and a lock for said knuckle, said lock being provided with means whereby it may interlockingly engage means for actuating said lock, to thereby prevent said lock from accidentally moving to unlocked position, and being adapted to be operatively assembled with lock actuating means in a plurality of 70 relations.

In testimony whereof I affix my signature.
ISAAC H. MILLIKEN.
